UNITED STATES PATENT OFFICE.

OTTO MALCHER, OF CHICAGO, ILLINOIS, **ASSIGNOR TO MALCHER ADDING MACHINE COMPANY, OF CHICAGO, ILLINOIS, A CORPORATION OF ILLINOIS,**

PRINTING MECHANISM FOR CALCULATING MACHINES.

1,318,398. Specification of Letters Patent Patented Oct. 14, 1919.

Original application filed March 19, 1914, Serial No. 825,782. Divided and this application filed April 28, 1918. Serial No. 231,344.

To all whom it may concern:

Be it known that I, Otto MALCHER, a citizen of the United States, residing at Chicago, in the county of Cook and State of Illinois, have invented certain new and useful Improvements in Printing Mechanism for Calculating-Machines, of which the following is a specification.

This invention has for its object the provision of mechanism of the class named which shall be of improved construction and operation.

The invention is exemplified in the combination and arrangement of parts shown in the accompanying drawings, and described in the following specification, and it is more particularly pointed out in the appended claims.

In the drawings—

Fig. 1 is a perspective view of a calculating machine with parts broken away showing the application of one embodiment of the present invention to a calculating machine.

Fig. 2 is a vertical longitudinal section of the machine shown in Fig. 1.

Figs. 3, 4 and 5 show details.

This application is a division of my application Serial No. 825,782, filed March 19, 1914. The calculating machine to which the printing mechanism forming the subject matter of the present invention is applied, comprises a casing 1 having a plurality of slides 2 supported therein by cross shafts 3, each slide being provided with a spring 4 tending to draw the slide to the left, as viewed in Fig. 2. Locking mechanism including a bar 5 is employed for holding the bars 2 in their retracted position against the tension of the springs 4 and each bar is provided with a series of keys 6 any one of which may be depressed to limit the movement of the corresponding bar 2 when released by its locking mechanism. There are nine keys for each bar and the amount of movement of the bar 2 will depend upon the particular key depressed. Each set of keys represents the digits in one of the decimal orders of a number to be included in a computation to be performed by the machine. Each bar 2 has an extension 7 provided with rack teeth for operating one of the units of a computing device. This general method

of operating the computing mechanism is well known in the art and need not be described further for the purpose of this application. A main drive shaft 8 is provided for operating the computing mechanism and a supplementary drive shaft 9 is connected with the operating lever and is given a complete rotation in the direction of the arrow in Fig. 2 during the return stroke of the lever. The printing mechanism utilized in the present machine is set and adjusted directly by the movement of the slides 2 and is operated upon the return movement of the handle or crank to record the numbers set up in the machine. That is to say, as the slides 2 move forwardly to perform the calculation upon the totalizer, this movement adjusts the printing segments to be described, so as to bring the proper type faces into alignment and during the return movement of the operating handle the printing operation takes place just prior to the restoration of all of the moving elements of the machine to their normal and inactive positions.

The slides 2 are each provided with extensions 10 and these extensions are offset relative to the slides, as shown in Fig. 1, so that they are arranged compactly at the center and rear of the machine and each extension is provided with a bifurcated upright 11 to which the printing segments, to be described, are connected. A casing 12 surrounds the extensions 10 of the slides 2 and is designed to inclose the printing mechanism and constitute a bearing for a shaft 13. A transverse bar 14 is interposed between the walls of the casing 12, adjacent the top thereof, and is provided with depending segmental guides 15, which guides are spaced one from the other. Each type guide is shouldered to form an extension 16. A type segment 17 is mounted for reciprocation in the shoulder portion of each guide 15 against the extension 16 thereof, said segment being provided at its lower terminal with an arm 18 which is journaled on the shaft 13. At the joint between each type segment 17 and its arm 18 is a stud 19 which is received in the bifurcated end of the upright 11 of the corresponding rack extension 10. When the slides 2 are released, the extensions 10 thereof will move therewith and swing the arms 18 and the

2

type segments 17 about the shaft 13 which movement is proportionate to the movement of the slide 2 and is regulated by the denominational key depressed. As shown in Fig. 4, the segment 17 is provided with outstanding ribs 20. Each type 21 is provided with a neck or extension 22 which at its terminal is offset to form a shoulder 23. The extensions 22 of the type rest between the ribs 20 of the segments 17 and bear against the face of the body of the guides 15. The type of each order are held in position by the next adjacent guide 15 with the exception of the type provided for the units denominational order which are held in place by a curved plate 24. Opposite the printing line each guide 15 is provided with a slot 25 in which the hammers operate and engage the shoulders 23 of the type, as will be herein- 20 after more fully described.

When the slides 2 are released and moved forwardly by their springs 4, the corresponding segments 17 are adjusted, bringing the proper type corresponding with the key depressed into the plane of the printing line and also into alinement with the coöperating hammer slots 25 of the guides 15. When the hammers are released in the manner to be explained, they will operate the type so set and move them forwardly against the ribbon and the platen to record the digits on the particular type in the printing line. This provision of independently movable type eliminates all load from the hammers and decreases the jar against the platen. It will be noted from Figs. 1 and 2, that normally all of the type, except the lowermost one, are located above the hammer slots 25 but that the lowermost 40 or zero type is normally in the plane of the printing line and hence if all the hammers are released without previously moving any of the segments 17, a series of zeros will be recorded.

Extending transversely across the casing 12 is a pair of shafts or supporting rods 26 upon which hammers 27 are mounted for reciprocation. Each hammer is operated by a spring 28 which, under normal conditions, is placed under tension tending to throw the hammer toward the platen. At the forward terminal of each hammer is a hook 29, Fig. 3, which projects into the hammer slot 25 of the alined type guide 15. As the coöperating segment is swung downwardly by the action of the slide 2, the shoulders or noses 23 upon the type of that segment will be drawn through the hammer hook 29 and said hook will engage one of 55 noses of the type at any of the adjusted positions of the segment 17. Under normal conditions the hammer hooks 29 each engage the coöperating zero type and hence if there is no adjustment of the machine 60 all hammers operated will print zeros.

There is one hammer provided for each printing unit which unit consists of a series of type 21, a guide 15 and segment 17.

Each hammer is provided, at its rear end, with a primary lock shoulder 30 and intermediate its ends with a secondary lock shoulder 31 which is in the form of a tooth having one side thereof beveled or sloped. A hammer lock shaft 32 is mounted under the hammers 27 adjacent to the primary 70 lock shoulders 30 and is interposed between the walls of the casing. A bell crank 33 is mounted upon the hammer lock shaft 32 and has the tail 34 thereof contacting with a cam 35 mounted upon the secondary drive 80 shaft 9. As this bell crank 33 is keyed to the hammer lock shaft 32, oscillation of the bell crank by the cam when the secondary drive shaft is rotated will oscillate the hammer lock shaft 32. The opposite arm of 85 the bell crank 33 is bent at right angles to the body thereof and extends in front of all of the primary lock shoulders 30 and holds the hammers against the action of their coöperating springs 28. Loosely 90 mounted upon the hammer lock shaft 32 are a plurality of bell cranks 36. Each bell crank has one arm 37 thereof located vertically and the opposite arm 38 thereof horizontally, the arm 38 being provided with a tooth 39 at its terminal which engages the secondary lock shoulder 31 of the adjacent hammer. One side of the vertical arm 37 of the bell crank is provided with an outwardly projecting pin 40 while a lip 41 100 extends from the other side of said arm in the same horizontal plane as the pin 40. Each bell crank is acted upon by a spring 42 to hold the tooth 38 in engagement with the coöperating secondary lock shoulder 31 105 of the coöperating hammer. In this way the pin 40 of one bell crank 36 operates against the lip 41 of the next adjacent bell crank of a lower denominational order. Each extension 10 of the slides 2 is provided with a shoulder 43 which is alined with the extremity of the arm 37 of the coöperating bell crank of that order. 110

As the slides 2 move forwardly the extensions 10 thereof move with them setting the corresponding segments 17 of the printing mechanism to bring the proper type into the plane of the printing line to correspond to the key depressed. This movement of the slides causes the shoulders 43 of the extensions 115 120 of the operating slides to contact with the alined vertical arms 37 of the bell cranks 36 and move said bell cranks against the tension of the springs 42. As the slides remain in their forward position during the operation of the primary drive shaft 8 and the first part of the rotation of the secondary drive shaft 9, the bell cranks 36 are held 125 in this position thus freeing the hammers corresponding to the slides which are moved 130

for that particular computing operation. Although the hammers are thus released from the bell cranks 36 in the denominations corresponding to the depressed keys, they 5 are not yet free to move forwardly under the tension of springs 28 for the reason that they are held by the bell crank 33. The printing operation must be accomplished while the slides are in their forward position 10 and before they are restored. The restoration of the slides to their inoperative position is accomplished during the latter part of the rotation of the secondary drive shaft 9 and the printing operation must 15 therefore be completed during the first part of the rotation of the secondary drive shaft. It will be seen from Fig. 2 that the bell crank 33 is held in position to restrain the hammers 27 by the cam 35 but that at the 20 very beginning of the rotation of the secondary drive shaft the tail 34 of the bell crank 33 will be released to permit the hammers 27 to move forwardly under the tension of their springs 28. The shape of the 25 cam 35 is such that almost immediately after the hammers have been permitted to move forwardly they will be returned by the bell crank 33, the tail 34 of which is restored to its initial position by the cam immediately 30 following the release of the tail to permit the forward movement of the hammers. Thus each hammer released by the bell cranks 36 will be reciprocated under the influence of its spring 28 to drive the type set 35 to coöperate with the hook 29 thereof against the ribbon to record a digit. The hammers which are not released by the bell cranks 36 for the reason that the corresponding slides have not been operated are held 40 in their retracted position against the influence of the springs 28 by said bell cranks. The cam surface of the cam 35 is of such a length that as soon as a record has been made by the type, the tail 34 of the bell 45 crank 33 rides upon the body of the cam and thereby oscillates said bell crank to return all of the hammers released to their normal and inactive positions, as illustrated in Fig. 2.

50 It is desirable and is the practice in machines of this character to print zeros at the right of the digit of the lowest order recorded and to accomplish this the pins 40 and lips 41 are provided. If the bell crank 55 36 of the hundredths denominational order is operated by its coöoperating slide 2 and the slides of the tens and units denominational orders are not operated to present a different type from the zero type to the operating 60 hammers, the pins 40 of the bell crank of the hundredths denominational order will engage the lip 41 of the bell crank of the tens denominational order and the pin 40 of the bell crank of the tens denominational order 65 will contact with the lip 41 of the units

denominational order and oscillate the bell crank 36 about the hammer lock shaft 32 to release the hammers of both the tens and units denominational orders. Hence when the bell crank 33 is oscillated about the hammer lock shaft 32, these hammers of the tens and units orders will be free to move under the influence of their coöperating springs 28 to drive the zero type toward the platen, thereby recording zeros without any adjustment of the segments 17. When the slides 2 are returned to their normal and inactive positions, the extensions 10 thereof will move rearwardly of the machine swinging all adjusted segments 17 back to their initial 80 positions and this will permit the bell cranks 36 which have been adjusted, to be moved by the springs 42 into engagement with the secondary lock shoulders 31. Prior to this, however, the printing operation has been completed as described and all of the hammers 27 which have been released have been returned to their original positions by the cam 35 operating against the tail 34 of the bell crank 33. 90

It should be noted that the type 21 are supported independently of the hammers 27 and that they are shifted into the printing position by mechanism independent of the printing hammers. When a particular type 95 is brought into printing position the hammer is interlocked with that particular type and remains connected with the type during the printing operation and moves the type forwardly to cause an impression to be made 100 upon the record sheet and also positively withdraws the type after the impression has been made. This makes it unnecessary to provide each individual type with a spring or other device for returning it after it has 105 been struck by the printing hammer. 110

I claim:

1. The combination with a plurality of guides, of segments reciprocating between said guides, type carried by said segments and held in place therein by said guides, and hammers arranged to selectively coöperate with said type. 115
2. The combination with guides, of a plurality of type holders movable independently of one another relative to said guides, type carried by said holders, and hammers arranged to successively interlock with said type as said holders are moved along their guides. 120
3. The combination with a plurality of guides, of segments coöoperating with said guides, a plurality of reciprocal type carried by said segments and held in place therein by said guides, and hammers arranged to engage said type and to reciprocate the same within said segments. 125
4. The combination with a movable type holder, of individually movable type carried thereby, and hammers arranged to success- 130

- 4
- sively engage the individual type carried by said holder when said holder is moved and to interlock therewith to form rigid connections between said hammer and type.
5. The combination with a plurality of guides, of a plurality of segments mounted to slide between said guides, individually movable type carried by a portion of said segments, and hammers slidably engaging 10 said type and arranged to successively cooperate therewith as the segments are adjusted.
6. The combination with a guide, of a type shifting member movable relative to 15 said guide, individually movable type carried by said type shifting member, a hammer arranged to successively engage said type as they are moved by said member, and rigid means on said guide for holding 20 said type in retracted position.
7. The combination with a plurality of guides each having a hammer slot therein, of segments operating between said guides, individually movable type carried by said 25 segments, and hammers extending into said hammer slots and arranged to successively engage said type upon the adjustment of said segments and to reciprocate one of said type after the completion of said adjustment.
8. In a printing device for calculating machines, a series of type members, a hammer for operating said type members, means for selectively holding said hammer in locking engagement with said members and means for operating said hammer to cause 35 a type member engaged thereby to produce an impression.
9. In a printing device for calculating 40 machines, a series of type members, a hammer for operating said type members, means for shifting said type members into locking engagement with said hammer, and rigid means for holding said type members in re- 45 tracted position when not in engagement with said hammer.
10. In printing mechanism for calculating 50 machines, a series of movable type members, a hammer for operating said type members to produce printed impressions, means for shifting said type members successively into locking engagement with said hammer, and rigid means for holding in retracted position the type members which are not in en- 55 gagement with the hammer.
11. In combination, a reciprocating hammer, a type member, means for shifting said type member into and out of operative engagement with said hammer, mechanism for 60 operating said hammer to cause a type member connected therewith to produce a printed impression, and means for connecting said hammer and type member when in engagement with one another so that said 65 type member will be moved in unison with said hammer in either direction of movement of said hammer.
12. In printing mechanism for calculating machines, a hammer, means for reciprocating said hammer, a type member movable 70 into and out of engagement with said hammer and operable by said hammer when in engagement therewith to produce a printed impression, and means on said hammer for retracting said type member after a print- 75 ing operation.
13. The combination with a reciprocating hammer, of a series of type members, means for shifting said type members to bring them successively into operative relation 80 with said hammer, means for reciprocating said hammer to cause a type member coöperating therewith to produce an impression, and means on said hammer for engaging a type member when in operative relation 85 with said hammer to cause said type member to move in either direction in unison with said hammer.
14. In combination, a bar, a series of type connected with said bar and slidably thereon, a printing hammer, means for holding said type in retracted position and means for shifting said bar to bring said type selectively into operative relation with said hammer and into engagement with said holding 95 means when not in operative relation with said hammer.
15. In combination, a bar, a series of type connected with said bar and slidably thereon, a hammer for operating said type to 100 cause said type to produce printed impressions, means for shifting said bar to bring said type successively into operative relation with said hammer, means on said bar for forming an interlocking engagement 105 with said type, and means for holding said type in retracted position when not in engagement with said hammer.
16. In combination, a type shifting bar, a series of type slidably connected with said 110 bar, a hammer for operating said type to cause said type to produce printed impressions, means for shifting said bar to successively bring said type into engagement with said hammer, means on said hammer 115 for holding said type to move in unison with said hammer but arranged to permit movement of said type into and out of engagement with said hammer, and means for holding said type in retracted position when out 120 of engagement with said hammer.
17. The combination with a series of type members, of a guide therefor, a reciprocating hammer for said type members, means on said guide for holding said type members in retracted position when said type members are out of operative engagement 125 with said hammers, means for successively shifting said type members into operative engagement with said hammer, and means 130

on said hammer for interlocking with said type as they are shifted into operative relation thereto, such interlocking means being arranged to cause said type to move in unison with said hammer in one direction to make an impression and in an opposite direction to retract said type after the impression has been made.

18. In printing mechanism for calculating machines, a plurality of movable type members, a hammer for operating said type members, means for shifting said type members to bring them selectively into engagement with said hammer, mechanism for reciprocating said hammer, and means on said hammer for engaging said type members to move said type members in one direction to produce a printed impression and to retract

said type members when said hammer is reciprocated in an opposite direction.

19. The combination with a series of type members, and a hammer for operating said members, said hammer and type members having interfitting portions thereon arranged to slide into and out of engagement with one another when moved in one direction relative to one another, said interfitting portions arranged to form when in engagement a rigid connection between said hammer and a particular type member connected therewith.

In testimony whereof I have signed my name to this specification on this 27th day of April, A. D. 1918.

OTTO MALCHER.
